UNITED STATES PATENT OFFICE

MICHAEL KIWAD, OF NEW YORK, N. Y., ASSIGNOR TO LA BELLE SPECIALTY CO. INC., A CORPORATION OF NEW YORK

DESIGN FOR A COMBINED ASH TRAY AND LAMP BASE OR ARTICLE OF ANALAGOUS NATURE

Application filed February 28, 1931. Serial No. 38,870. Term of patent 3½ years.

To all whom it may concern:

Be it known that I, MICHAEL KIWAD, a citizen of the United States of America, and a resident of the city of New York, in the county of Bronx and State of New York, have invented a new, original, and ornamental Design for Combined Ash Tray and Lamp Base or Article of Analogous Nature of which the following is a specification, reference being had to the accompanying drawing, forming a part hereof.

In the drawings:

bined ash tray and lamp base or article of analogous nature, taken from one side, the other side being similar to the side shown, and

Figure 2 is a diagrammatic top plan view in outline.

I claim:

The ornamental design for a combined ash tray and lamp base or article of analogous nature substantially as shown.

MICHAEL KIWAD.
